(57) **CLAIM**

The ornamental design for a decorative accessory for a wine bottle, as shown and described.

DESCRIPTION

FIG. 1 is an environmental front elevational view of a decorative accessory for a wine bottle showing my new design;

FIG. 2 is a rear elevational view thereof;

FIG. 3 is a right side elevational view thereof;

FIG. 4 is a left side elevational view thereof; and,

FIG. 5 is a top plan view thereof.

The broken line showing of the wine bottle in FIG. 1 is for illustrative purposes only and forms no part of the claimed design. The broken line showing of the simulative grapes in FIG. 1 is for illustrative purposes only, merely disclosing the types of ornamentation which may be used in the present invention, and forms no part of the claimed design.
